DESIGN FOR A MASK FOR DOLLS OR SIMILAR ARTICLE

Henry Levy, New York, N. Y.

Application October 22, 1942, Serial No. 108,592

Term of patent 3½ years

To all whom it may concern:

Be it known that I, Henry Levy, a citizen of the United States, residing in New York, county and State of New York, have invented a new, original, and ornamental Design for a Mask for Dolls or Similar Article, of which the following is a specification, reference being had to the accompanying drawing, forming part thereof.

Figure 1 is a front view of a mask for dolls or similar article, showing my new design; and Figure 2 is a side perspective view thereof.

I claim:

The ornamental design for a mask for dolls or similar article, as shown.

HENRY LEVY.
